UNITED STATES PATENT OFFICE.

GEORGE SHATSWELL, OF WAUKEGAN, ILLINOIS, ASSIGNOR TO HIMSELF
AND ELIJAH M. HAINES, OF SAME PLACE.

IMPROVED FASTENING FOR RAILWAY-RAILS.

Specification forming part of Letters Patent No. 102,873, dated May 10, 1870.

To all whom it may concern:

Be it known that I, GEORGE SHATSWELL, of Waukegan, in the State of Illinois, have invented certain Improvements in Fastenings for Railway-Rails, of which the following is a specification.

The nature and object of the invention is to provide a simple, cheap, and efficient means of uniting or joining the ends of rails on railroads.

Hitherto great difficulty has existed in uniting the ends of rails, when placed in position, in a sufficiently strong manner to resist the heavy pressure that is brought to bear upon them by the passing train. This difficulty is largely owing to the contracting and expanding of the rails through the influence of cold and heat.

In the drawings, Figure 1 is a perspective view of two ends of rails united or joined in position. Fig. 2 is a section of a rail, showing one form of the side piece placed at the side of the rail, and also one form of the recesses cut in the flanges, and the way of fastening the side pieces to the rails. Fig. 3 is a view of another form of side pieces and the recesses cut in the upper and lower flange.

I dispense with the use of bolts and nuts in my fastenings.

Similar letters refer to similar parts in the different drawings.

A A are the rails placed in position.

B B is a side piece located on the side of each end of the rail, between the upper and lower flanges, and resting in the recesses C C. There are two of these—one on each side of the rails.

Next to and on either side of the stem there is cut a groove or recess in the upper and lower flange, as seen at C C, into which fit the side pieces, B B. These recesses are cut closely

to the stem, and sufficiently deep and of sufficient length in the flanges to give support to the side pieces, B B. These recesses are cut in each end of the rail, and the side pieces fit into the recesses, and extend from one rail to another, and thus pass by the joint made by the uniting of the two rails, thus uniting the two rails and holding them together without the use of bolts or punching any holes through the rails, as is done in the old method.

I can use a square recess or groove, as shown in Fig. 2, or a round one, as is shown in Fig. 3.

I can use a side piece in the form shown in Fig. 2, or one without a shoulder, as shown in Fig. 3.

In constructing this improvement, the rail is made with the recess cut as before described.

The side pieces, B B, are inserted in the recesses of one rail, and are then slipped into the recesses of the other rail, thus uniting the two rails.

It will readily be observed that the rail is left to freely contract and expand through the influences of heat and cold, and at the same time the strength and effect of this means of uniting or fastening the ends of the rails are not in the least impaired.

I make use of the ordinary rail, and rely upon grooves or recesses cut in the top and bottom flanges to make my fastenings.

I claim—

A fastening for railway-rails, consisting of the side pieces or bars, B B, held against the shank of the rails at their junction by the grooves *cccc* in the head and base of the ordinary rail, as set forth.

GEORGE SHATSWELL.
